ROBERT J. HEWETT, OF WESTFIELD, NEW JERSEY.

DIRECTIONALLY-CONTROLLED SIGNAL SYSTEM.

1,362,994.

Specification of Letters Patent. Patented Dec. 21, 1920.

Application filed May 23, 1918. Serial No. 236,134.

To all whom it may concern:

Be it known that I, ROBERT J. HEWETT, a citizen of the United States, residing at Westfield, in the county of Union and State 5 of New Jersey, have invented certain new and useful Improvements in Directionally-Controlled Signal Systems, of which the following is a full, clear, and exact description.

This invention relates to block signaling 10 systems and more particularly to directionally controlled signal systems, which are sometimes referred to as absolute permissive block signal systems. One of the objects of the invention is to provide a signaling 15 system of this character, in which normally closed circuits are utilized for obtaining the direction control of the signals.

Other objects of the invention are to provide a system of this character, in which 20 the circuit arrangements are of a simple character, and the directional control circuits are controlled by normally energized relays.

The invention will be clear from the description hereinafter to follow, when taken 25 in conjunction with the accompanying drawings, in which—

Figures 1 and 2 of the drawings taken 30 together show one embodiment of the invention.

In the drawings, a single stretch of track is shown between two sidings, designated W and X, respectively, which single stretch of track is divided into track sections T⁹, 35 T¹⁰, T¹¹, T¹², T¹³, T¹⁴, T¹⁵ and T¹⁶. These track sections are equipped with the usual track circuits, which include the track relays R⁹ to R¹⁶, respectively. The eastbound traffic through the stretch of track is controlled by signals 10, 12 and 14, signals 40 10 and 14 being situated at the end of the stretch of track and signal 12 being an intermediate signal. In the same manner, the westbound traffic through the stretch of track is controlled by signals 9, 11 and 13, which are disposed in a similar manner. The signals 9 and 10 at the passing siding W and the signals 13 and 14 at the passing 45 siding X are controlled by a usual type of control circuit and the directional control is not applied to these signals but is applied to the intermediate signals 11 and 12, which are provided with normally energized stick relays for providing the directional control, 50 as will be hereinafter described.

Referring first to the control circuits for

each of the signals, these circuits are of the usual polarized type for governing semaphore signals having three operative positions. The circuit for the line relay L¹⁰ at 60 passing siding W is as follows: from line relay L¹⁰, wire 20, contact 21^a of track relay R¹⁰, line wire 22^b, contact 23^b of track relay R¹¹, wire 24, absolute control contact 25^b of eastbound stick relay S¹², wire 26, absolute 65 control contact 27^a of eastbound control relay L¹², wire 28, positive pole changer P of signal 12, wires 29, 30 and 31, battery B¹², wires 32 and 33 to negative pole changer N of signal 12, and to the common wire C, back 70 to the common side of the line relay L¹⁰. When the stick relay S¹² is deenergized, the absolute control of line relay L¹⁰ through the contact 25^b of stick relay S¹² will be open and the permissive control will be established as follows: from wire 24, back contact 75 34^a, wire 35, wire 28 to pole changer P, the portion of the circuit thus traced being in parallel to the circuit previously traced. Or in other words, the control circuit for the 80 line relay L¹⁰ may be closed when the stick relay S¹² is energized or deenergized, as will be hereinafter referred to.

The line control circuit for the intermediate eastbound signal 12 is as follows: 85 from the line control relay L¹², wire 20, contact 21^b of track relay R¹², line wire 22^c, contact 25^c of track relay R¹³, wire 26, contact 27^b of track relay R¹⁴, line wire 28, contact 29^c of track relay R¹⁵, wire 30, positive 90 pole changer P of signal 14, wires 31 and 32 to battery B¹⁴, wire 33, negative pole changer N to the common wire C, back to the line relay L¹². The control circuit for the line control relay L¹⁴ is only partially 95 shown and is as follows: from line control relay L¹⁴, wire 20, contact 21^c of track relay R¹⁶ to line wire 22^d, and thence to the eastbound signal in advance.

The circuits for controlling the line control relays L⁹, L¹¹ and L¹³ of the westbound signals are similar, and will be referred to later.

The signals 10, 12 and 14 for eastbound traffic are of the three-position type and 105 the line control relays for controlling these signals are of a type known as neutral polar relays, and the circuits for controlling each of the signals are identical, and will be explained by referring to signal 10. The 110 signal 10 has two local circuits, one for controlling its 45° position and the other for

controlling its 90° position, the signal being in its zero position when both of these circuits are open. The circuit for the 45° position is as follows: from the positive terminal of the battery B¹⁰, wire 28, wire 44, contact 50^b of line control relay L¹⁰, wire 51, to the signal 10, wire 52 and wire 29, back to the battery B¹⁰. The circuit for the 90° position of the signal is as follows: 5 from the battery B¹⁰, wire 28, wire 44, contact 50^b, wire 53, contact 54^b, which is controlled by a polarized armature, wire 55 to signal 10, wire 52 and wire 29 back to the battery B¹⁰. The line relay L¹⁰ is adapted 10 to be energized in a normal or reverse condition by currents passing through the circuit in opposite directions which are controlled by the pole changers P and N at the signal 12. When current of a normal condition 15 is passing through the line relay L¹⁰, both contacts 50^b and 54^b are closed to close the motor circuit for the 90° position of the signal. When, however, current of a reverse condition is passing through the circuit 20 the neutral contact 50^b alone will be closed to close the motor circuit for the 45° position, the 90° position being open at the contact 54^b. The neutral polar line relays at all of the other signals control the 45° 25 and 90° motor circuits in the same manner and need not be further referred to other than to state that the contacts 50^c and 54^c control the motor circuits for the signal 12, contacts 50^d and 54^d the motor circuits for 30 the signal 11, the contacts 50^e and 54^e the motor circuits for the signal 13, and the contacts 50^f and 54^f the motor circuits for the signal 14.

In tracing the circuit for the line relay 40 L¹⁰ it was stated that the circuit for this relay was controlled by the stick relay S¹², the circuit being closed by the front contact 25^b of this relay when the stick relay is energized and by the back contact 34^a when 45 the stick relay is deenergized, the circuits through these two contacts being in parallel or multiple with each other.

Referring now to the circuit for the stick relay S¹², this circuit is normally energized 50 by a local circuit, which is as follows: from the positive terminal of the battery B¹², wire 31, wire 36, contact 37^a, wires 38 and 39, stick relay S¹², wires 40 and 32 to the negative terminal of the battery B¹². This 55 type of circuit is commonly known as a holding circuit, since it includes an armature of the relay, which will maintain the circuit closed until the relay S¹² is shunted, as will be later described. The stick relay S¹² is 60 also provided with a restoring circuit for again energizing the relay after it has been deenergized. This circuit is normally open and is in multiple with the contact 37^a, the circuit being as follows: from battery B¹², 65 wires 31, 30 and 44, contact 43^a of the line

control relay L¹², wire 43^c, circuit controller 48^a (which is closed when the signal 12 is at its danger or stop position), wires 42, 41, and 39, stick relay S¹² and wires 40 and 32, back to the battery B¹². It will therefore 70 be seen that this restoring circuit for the stick relay S¹² is controlled by the line control relay L¹², and is therefore only closed after the line control relay L¹² has again become energized upon a train passing 75 through the track section, as will be later referred to.

The shunting circuit for controlling the deenergization of the stick relay S¹² includes a back contact 46^a of track relay R¹², the 80 circuit being as follows: from the stick relay S¹², wire 39, wire 41, wire 45, back contact 46^a (which is normally open), wire 47, circuit controller 48 (which is normally closed when the signal 12 is at its 45° or 90° 85 position), wires 49, 33 and 40, to the stick relay S¹². The current from the battery B¹², which normally passes from the wire 38 to the wire 39 and thence to the stick relay S¹², will, when this circuit is closed, pass 90 instead of to the wire 39, to the wire 45, and through the circuit as traced, back to the point where the wire 40 is connected to the wire 33; or in other words, when the track relay R¹² is deenergized its back contact 95 will close a circuit to the battery B¹², which is in parallel to the stick relay S¹², and since the latter branch of the circuit is of greater resistance, it will be shunted and the relay deenergized. However, just as soon as the 100 stick relay is deenergized by virtue of the formation of this shunt circuit, the shunt itself will be opened by the opening of contact 37^a. The battery B¹² will therefore be on the shunt circuit for a very short interval of time, which is just sufficiently long to permit the stick relay S¹² to be deenergized. After the stick relay is deenergized it can only again be energized by the closing 110 of the restoring circuit, which is controlled by the restoring contact 43^a and the circuit controller 48^a of the signal 12. The circuits for controlling the westbound signals 9, 11 and 13 are similar to those for the eastbound signals just described, and will be 115 briefly referred to. The signal 9 is controlled by the line control relay L⁹, only a portion of whose circuit is shown, starting from the common wire C, passing through the line relay L⁹ to wire 60, to contact 61^a of 120 track relay R⁹ and line wire 62^a to the signal in advance. The signal 11 is controlled by the line control relay L¹¹, whose circuit is as follows: from the line control relay L¹¹, wire 60, contact 61^b of track relay R¹³, line 125 wire 62^b, contact 65^a of track relay R¹², wire 66, contact 67^a of track relay R¹¹, line wire 68, contact 69^a of track relay R¹⁰, wire 70 to pole changer P of signal 9, wires 71 and 72, to battery B⁹, wire 73^a to negative 130

pole changer P of signal 9, to the common wire C, back to the line control relay L¹¹. It will therefore be seen that this circuit is controlled in the same manner as is the 5 circuit for the line control relay L¹².

The line control relay L¹³ is similar to the circuit for the line control relay L¹⁰, but passes in the opposite direction, the circuit being as follows: from line control relay 10 L¹³, wire 60, contact 61^c of track relay R¹⁵, wire 62^c, contact 63^b of track relay R¹⁴, wire 64, contact 65^b of stick relay S¹¹, wire 66, contact 67^b of line relay L¹¹, wire 68, pole changer P of signal 11, wires 69, 70 and 71 15 to track battery B¹¹, and wires 72 and 73, to common wire C, back to the line relay L¹³.

When the stick relay S¹¹ is deenergized this circuit will be open at the contact 65^b and the permissive control will be established 20 as follows: from wire 64 to back contact 74, wire 75, wire 68 to the pole changer P at signal 11, to the battery B¹¹, back to the common wire C, as described before.

The circuits for the stick relay S¹¹, while 25 performing the same functions as the circuits described in conjunction with the stick relay S¹², are somewhat varied, providing a different means for deenergizing the normally energized stick relay S¹¹. This means 30 consists of a differential winding 45^a upon the stick relay S¹¹. The circuit normally energizing the stick relay S¹¹ is as follows: from the battery B¹¹, wire 71, wire 36, contact 37^b of the stick relay S¹¹, wire 38, wire 39, stick relay S¹¹, wire 40, wire 72, back to the battery B¹¹. This circuit is normally 35 closed and is a stick or holding circuit similar to the circuit for the stick relay S¹². To deenergize the stick relay S¹¹ the differential winding 45^a is used, the circuit through 40 this winding being as follows: from the battery B¹¹, wires 71 and 36, contact 37^b of stick relay S¹¹, wire 38, wire 39^a, differential winding 45^a, wire 45, back contact 46^b of 45 track relay R¹³, wire 47, circuit controller 48 of signal 11, wires 49, 73 and 72, back to the battery B¹¹. The winding 45^a is wound opposite to the main winding of the stick relay, so that when this last named circuit is 50 closed at the contact 46^b the stick relay S¹¹ will be deenergized and the opening of the contact 37^b will open both the stick circuit and the deenergizing or shunting circuit described. The relay then remaining deenergized until it is restored by the restoring 55 circuit, which is as follows: from the battery B¹¹, wires 71, 70 and 44, contact 43^b of line relay L¹¹, wire 43^c, circuit controller 48^a, wires 41 and 39, stick relay S¹¹, wires 40 and 60 72 back to the track battery B¹¹. It will therefore be seen that this restoring circuit is controlled by the line relay L¹¹ in the same manner as is the restoring circuit for the stick relay S¹² controlled by the contact 65 43^a of the line relay L¹².

The pole changers N and P are operated by their corresponding signal device. When a signal device is in either its 45° or its 90° position its pole changers N and P will be in their normal position as shown, 70 and the current will pass through the line relay controlled by the particular pole changer in one direction to hold its polarized contact device closed. When the signal device changes to its 0° position, the 75 pole changer governed thereby will be operated to reverse the current through its line relay and open its polarized contact device. The opening of this contact device as a signal goes to "stop" position puts the signal 80 controlled by it in its 45° position.

It is believed that with the above description of the relays and circuit arrangements, the operation of the system will be clear, and first referring to the movement of an 85 eastbound train through the stretch of single track: the entry of the eastbound train into track section T⁹ by deenergizing the track relay R⁹ will open its contact 61^a in the control circuit for the westbound control relay L⁹, which will put the signal 9 90 to stop and consequently reverse the pole changers N and P. As before described, the pole changers N and P at signal 9 control the circuit for the line relay L¹¹, so that the 95 current which will now pass through the line relay L¹¹ will reverse its polarity and open its polar contact 54^d, which will break the 90° motor circuit of the signal 11, but will hold the 45° motor circuit closed at 100 contact 50^d.

The entry of the eastbound train into track section T¹⁰ will deenergize track relay R¹⁰ and its contact 21^a will open the control circuit for the line control relay L¹⁰, which will 105 put the signal 10 to stop. The deenergization of the track relay R¹⁰ will also open contact 69^a, which controls the line relay L¹¹ of the westbound traffic and the signal 11 will then go to stop. The deenergizing of 110 the line control relay L¹¹ will, by opening its contact 67^b, open the circuit for the westbound control relay L¹³, which will cause the westbound signal 13 to go to stop.

It will therefore be seen that when an 115 eastbound train enters the track section T¹⁰ the westbound signal 13 at the other end of the stretch of track goes to stop, which sets the route against westbound train movements, which is frequently referred to as the 120 absolute control against westbound train movements. When the train is in the track section T¹¹ the track relay R¹¹ is deenergized, which will hold open the circuit to the line relay L¹⁰ at contact 23^b, and the circuit to 125 the line relay L¹¹ at contact 67^a. The circuits will therefore remain in the same condition as when the train was in track section T¹⁰. When the train enters track section T¹², the relay R¹² being deenergized, 130

will close its back contact 46^a, which closes the shunt circuit of the stick relay S¹² as previously described, which causes the deenergization of the stick relay, and hence the 5 opening of its retaining contact 37^a. This stick relay will therefore remain deenergized until its restoring circuit is closed, as will be referred to later.

The opening of front contact 25^b of stick 10 relay S¹² will open the circuit which controls the absolute control of line relay L¹⁰ and establish the permissive control for this relay, so that as soon as the train enters track section T¹² the control circuit for the 15 line control relay L¹⁰ will be as follows: from line control relay L¹⁰, wire 20, contact 21^a of track relay R¹⁰, line wire 22^b, contact 23^b of track relay R¹¹, back contact 34^a wires 35 and 28 to the negative pole 20 changer N, which is now reversed by the stop position of the signal 12, wires 33 and 32, to battery B¹², wires 31, 30 and 29 to positive pole changer P and from thence to the common wire C, back to the line control 25 relay L¹⁰ at the signal 10.

The reverse current which now passes through this circuit, due to the actuation of the pole changers, will cause line control relay L¹⁰ to be energized with reverse polarity and cause its polarized contact 54^b to move to its open position, but closes the neutral contact 50^b and the motor circuit for the 45° position. This will permit a second train to pass the signal 10, in accordance 35 with the permissive rule.

While an eastbound train is in track section T¹², T¹³, T¹⁴, and T¹⁵, the line control relay L¹² will remain deenergized, since the circuit for this line relay is controlled by the 40 track relays of these sections. Upon the entry of the train into track section T¹⁶ the energization of track relay R¹⁵ will close the line control circuit for line control relay L¹² and the energization of this relay will close 45 the restoring circuit for the stick relay S¹² at the contact 43^a, which is controlled by this contact and the circuit controller 48^a, which remains closed while the signal 12 is at stop. The energization of the stick relay 50 S¹² will again close its holding circuit and restore this relay to its normal or absolute position.

While the eastbound train is in track section T¹³, the deenergization of the track relay R¹³ will close the back contact 46^b, but this will not close the circuit through the differential winding 45^a which remains open at circuit controller 48, since the signal 11 is at its stop position, and hence the stick relay will remain energized.

When the eastbound train enters track section T¹⁴ the track relay R¹³ will be energized and by the closing of its contact 61^b the control circuit for the westbound signal 11 will

be closed, which will clear this signal in the 65 rear of the eastbound train; and it might be here stated that as the train clears out of track section T⁹ the closing of the contact 61^a of track relay R⁹ will also clear the westbound signal 9 to the rear of the eastbound 70 train.

The movement of a westbound train through the stretch of track is similar to the one described for the eastbound train, the passage of a westbound train through 75 the track sections causing a deenergization of the stick relay S¹¹, as the westbound train enters track section T¹³, to establish the permissive control similar to the manner in which the permissive control is established 80 by the entry of an eastbound train into track section T¹². In the same manner, the absolute control against eastbound trains is established by the entry of a train into track section T¹⁵, which opens the contact 29^c of 85 track relay R¹⁵, which is included in the circuit of the line control relay L¹², which will cause the signal 12 to go to stop. Also the deenergizing of the line control relay L¹² will break the circuit of the line control relay L¹⁰ at the contact 27^a, which will cause the signal 10 to go to stop, and set the route 90 against eastbound trains. The further movement of the westbound train through the track causes similar operation of the signals, as did the movement of an eastbound train, and need not be further described.

At signal 12 it will be noted that line control relay L¹² is symbolized as a slow releasing relay. The purpose of this is as follows: Normally energized stick relay S¹² is deenergized by being put on short circuit by back contact 46^a of track relay R¹². Stick relay S¹² is therefore inherently a slow releasing relay and will not be entirely deenergized until after a certain time interval 100 elapses after back contact 46^a is closed. The short circuit on stick relay S¹² is initiated by back contact 46^a of track relay R¹² and is effective until circuit controller 48 of signal 110 12 has passed below the 45° position, after which the short circuit will be broken. Stick relay S¹² must therefore be deenergized during the movement of circuit controller 48 from its 90° position to a point 115 below the 45° position. Variations in the resistance of back contact 46^a may lengthen the time interval necessary to deenergize stick relay S¹². In order to take care of this latter condition line relay L¹² may be slow 120 releasing as shown, which, by holding closed its contact 50^b a short interval of time, will delay the movement of signal 12 from its 90° position downward and likewise its circuit controller 48 will remain closed a longer 125 interval of time. This lengthened short circuit time interval should always be sufficient to deenergize stick relay S¹².

At signal 11, normally energized stick relay S^{11} is deenergized by a differential winding 45^a which sets up an opposing field and is therefore instantaneous in its deenergizing effect. Line relay L^{11} need not be slow releasing.

I claim:

1. In a directionally controlled block signal system, a stretch of single track divided 10 into block sections, track relays for said block sections, a plurality of signals along the trackway, normally closed overlapping line circuits for controlling said signals, said track relays controlling said circuits to open 15 all of them when a train passes into the stretch of track in one direction to thereby set the route against trains traveling in the opposite direction, a normally open auxiliary circuit in multiple with one of said 20 line circuits, and a relay operative to open said last named line circuit and to close said auxiliary circuit when a train passing through the stretch of track in the said opposite direction reaches an intermediate 25 point to thereby actuate the signal to the rear of the train to permit a train traveling in the same direction to proceed and to open said auxiliary circuit and close said line circuit in multiple therewith when the train 30 passes out of the stretch of track.
2. In a directionally controlled block signal system, a stretch of single track divided 35 into block sections, track relays for said block sections, a plurality of signals along the trackway, normally closed overlapping line circuits for controlling said signals, said track relays controlling said circuits to open all of them when a train passes into the stretch of track in one direction to thereby 40 set the route against trains traveling in the opposite direction, a normally open auxiliary circuit in multiple with one of said line circuits, and a normally energized stick relay operative to open said last named line 45 circuit and to close said auxiliary circuit when a train passing through the stretch of track in the said opposite direction reaches an intermediate point to thereby actuate the signal to the rear of the train to permit a train traveling in the 50 same direction to proceed and to open said auxiliary circuit and close said line circuit in multiple therewith when the train passes out of the stretch of track.
3. In a directionally controlled block signal system, a stretch of single track divided 55 into block sections, track relays for said block sections, a plurality of signals along the trackway, normally closed overlapping line circuits for controlling said signals, said track relays controlling said circuits to open all of them when a train passes into the stretch of track in one direction to thereby 60 set the route against trains traveling in the same direction.

opposite direction, a normally open auxiliary circuit in multiple with one of said line circuits, a circuit closer in control of both the said auxiliary circuit and line circuit, and a relay in control of the circuit closer operative to open the line circuit and 65 close the auxiliary circuit when a train passing through the stretch of track in the said opposite direction reaches an intermediate point to thereby actuate the signal to the rear of the train to permit a train traveling 70 in the same direction to proceed and to open the auxiliary circuit and close the line circuit in multiple therewith when the train passes out of the stretch of track.

4. In a directionally controlled block signal system, a stretch of single track divided 75 into block sections, track relays for said block sections, a plurality of signals along the trackway, normally closed overlapping line circuits for controlling said signals, 80 said track relays controlling said circuits to open all of them when a train passes into the stretch of track in one direction to thereby set the route against trains traveling in the opposite direction, a normally open auxiliary circuit in multiple with one of said line circuits, and means for opening said last named line circuit and for closing said auxiliary circuit when a train passing 85 through the stretch of track in the said opposite direction reaches an intermediate point to thereby actuate the signal to the rear of the train to permit a train traveling in the same direction to proceed and for opening said auxiliary circuit and closing 90 said line circuit in multiple therewith when the train passes out of the stretch of track, said means including a normally energized relay having a holding circuit, a differential winding on said relay, a circuit for said differential winding, and a restoring circuit 95 for said relay.

5. In a directionally controlled block signal system, a stretch of single track divided 100 into block sections, track relays for said block sections, a plurality of signals along the trackway, normally closed overlapping line circuits for controlling said signals, said track relays controlling said circuits to open all of them when a train passes into the 105 stretch of track in one direction to thereby set the route against trains traveling in the opposite direction, a normally open auxiliary circuit in multiple with one of said line circuits, and means for opening said last 110 named line circuit and for closing said auxiliary circuit when a train passing through the stretch of track in the said opposite direction reaches an intermediate point to thereby actuate the signal to the rear of the 115 train to permit a train traveling in the same direction to proceed and for opening said auxiliary circuit and closing said line circuit 120

125

- in multiple therewith when the train passes out of the stretch of track, said means including a relay having a holding circuit, a deenergizing circuit controlled by said relay 5 and a restoring circuit.
6. In a directionally controlled block signal system, a stretch of single track divided into block sections, track relays for said block sections, a plurality of signals along the trackway, normally closed overlapping line circuits for controlling said signals, said track relays controlling said circuits to open all of them when a train passes into the stretch of track in one direction to thereby 10 set the route against trains traveling in the opposite direction, a normally open auxiliary circuit in multiple with one of said line circuits, and means for opening said last named line circuit and for closing said auxiliary circuit when a train passing through 15 the stretch of track in the said opposite direction reaches an intermediate point to thereby actuate the signal to the rear of the train to permit a train traveling in the same direction to proceed and for opening said auxiliary circuit and closing said line circuit in multiple therewith when the train passes out of the stretch of track, said means including a relay having a holding circuit controlled by said relay, a differential winding 20 for said relay, a circuit for said differential winding controlled by said relay and a restoring circuit for said relay.
7. In a directionally controlled block signal system, a stretch of single track divided into block sections, track relays for said block sections, a plurality of signals along the trackway, normally closed overlapping line circuits for controlling said signals, said 25 track relays controlling said circuits to open all of them when a train passes into the stretch of track in one direction to thereby set the route against trains traveling in the opposite direction, a normally open auxiliary circuit in multiple with one of said line circuits, and means for opening said last named line circuit and for closing said auxiliary circuit when a train passing through 30 the stretch of track in the said opposite direction reaches an intermediate point to thereby actuate the signal to the rear of the train to permit a train traveling in the same direction to proceed and for opening said auxiliary circuit and closing said line circuit in multiple therewith when the train passes out of the stretch of track, said means including a relay having a holding circuit controlled by said relay, a differential winding 35 for said relay, a circuit for said differential winding controlled by said relay and a restoring circuit for said relay.
8. In a directionally controlled block signal system, a stretch of single track divided into block sections, track relays for said block sections, a plurality of signals along the trackway, normally closed overlapping line circuits for controlling said signals, said 40 track relays controlling said circuits to open all of them when a train passes into the stretch of track in one direction to thereby set the route against trains traveling in the opposite direction, a normally open auxiliary circuit in multiple with one of said line circuits, and means for opening said last named line circuit and for closing said auxiliary circuit when a train passing through 45 the stretch of track in the said opposite direction reaches an intermediate point to thereby actuate the signal to the rear of the train to permit a train traveling in the same direction to proceed and for opening said auxiliary circuit and closing said line circuit in multiple therewith when the train passes out of the stretch of track, said means including a normally energized relay having 50 a holding circuit controlled thereby, a deenergizing circuit controlled by a track relay, and a restoring circuit controlled by a relay in a line control circuit and a circuit controller actuated by 55 its corresponding signal.
9. In a directionally controlled block signal system, a stretch of single track divided into block sections, track relays for said block sections, a plurality of three-position signals along the trackway arranged at the ends and intermediate the stretch of track, normally closed overlapping line circuits for controlling said signals, an auxiliary circuit in multiple with the line circuit of one of the signals, a normally energized relay for maintaining said auxiliary circuit open, and means for deenergizing said last named relay when a train passes through the track section in one direction but not in the other.
10. In a directionally controlled block signal system, a stretch of single track divided into block sections, track relays for said block sections, a plurality of three-position signals along the trackway arranged at the ends and intermediate the stretch of track, normally closed overlapping line circuits for controlling said signals, an auxiliary circuit in multiple with the line circuit of one of the signals, a normally energized relay for maintaining said auxiliary circuit open, and means for deenergizing said last named relay when a train passes through the track section in one direction but not in the other, said means including a holding circuit for said relay controlled by said relay, a deenergizing circuit controlled by a track relay and a circuit controller at the intermediate signal and a restoring circuit for said normally energized relay.
11. In a directionally controlled block signal system, a stretch of single track divided into block sections, track relays for said block sections, a plurality of three-position signals along the trackway arranged at the ends and intermediate the stretch of track,

normally closed overlapping line circuits for controlling said signals, an auxiliary circuit in multiple with the line circuit of one of the signals, a normally energized relay for maintaining said auxiliary circuit open, a holding circuit for said relay, a de-energizing circuit for said relay controlled by a track relay, a circuit controller actuated

by the intermediate signal, a line relay in another of the overlapping line circuits, and 10 a restoring circuit for said normally energized relay controlled jointly by said circuit controller and the last mentioned line relay.

In witness whereof I subscribe my signature.

ROBERT J. HEWETT.
